ABSTRACT OF THE DISCLOSURE

A perfume composition uses

as an olfactory ingredient in a perfume carrier. R₁ is 25 methyl or ethyl and R₂ is branched or nonbranched alkyl having 3-5 carbon atoms. The preferred species of ingredient in the carrier is β ,2-dimethyl-5-isopropyl styrene.

The present invention relates to perfume compositions and novel components thereof that serve as olfactory ingredients.

The olfactory ingredients of perfume compositions with which the present invention is concerned have the general formula

in which R₁ is methyl or ethyl and R₂ is a branched or straight chain alkyl group containing 3-5 carbon atoms, and which may be propyl, isopropyl, butyl, isobutyl, tert.-butyl, pentyl, isopentyl, or the like. The preferred group for R₂ is isopropyl.

One species of the above genus is in the prior art per se but not as an olfactory material. This is the species in which R₁ is methyl and R₂ is isopropyl, namely, β ,2-dimethyl 5-isopropyl styrene (R. Lalande and J. P. Pillion in C. R. Acad. Sci. Paris, 258 (1964), No. 6, 1830-2).

The present invention comprises the discovery that the above group of styrene derivatives, especially β ,2-dimethyl 5-isopropyl styrene, have high odor value per se and in perfume compositions.

As the odors are reminiscent of vetiver, galbanum, and angelica oil, the styrene derivatives as mentioned above are very valuable in perfumery. They can be blended with other perfume constituents to obtain specific perfume compositions having widely varying characteristics. As used herein, the term "perfume compositions" of course includes not only perfumes which are applied as such, but also the other compositions in which perfumes are incorporated such as cosmetics, soaps, lotions, aerosols, creams, powders, and the like. The invention also comprises the discovery of a number of new species of the above genus, which are new per se and which also possess the above desirable perfume characteristics.

Accordingly, it is an object of the present invention to

provide perfume compositions and novel components thereof, which are relatively simple and inexpensive to manufacture and which have high odor value and desirable blending properties with other perfume components.

The styrene derivatives of the above group exist in stereo-isomeric forms, depending on the orientation of the methyl and the hydrogen that are attached at the β -position. Both trans- and cis-isomers but especially the former have the properties of the present invention.

To prepare the above styrene derivatives, there may be conducted a Friedel-Crafts reaction between a suitable compound having the formula

and propionyl chloride, thereby to produce an aromatic ketone having the formula

R₁ and R₂ being as described above. The ketone is reduced 35 to the corresponding carbinol having the formula

which is in turn dehydrated with acid to the styrene having the formula first given above. This is the method described by Lalande and Pillion, supra, for the production of β ,2-dimethyl 5-isopropyl styrene; and specifically β -methyl 2-ethyl 5-isopropyl styrene may be produced by the use of 1-ethyl 4-isopropyl benzene; while β ,2-dimethyl 5-tert.-butyl styrene may be produced by using 1-methyl 4-tert.-butyl benzene as the starting material, it being understood that the other species may be produced by using the corresponding di-substituted benzene as the starting material.

Examples of perfume compositions according to the present invention are as follows.

EXAMPLE I

	Parts by weight
60 Hyacinth composition:	
Isoamyl salicylate	340
Phenylethyl alcohol	250
Cinnamic alcohol	150
Citronellol	100
Phenylacetalddehyde dimethylacetal	50
Hydrotropic aldehyde	30
β ,2-dimethyl 5-isopropyl styrene	2
Petitgrain oil	2
Citronellyl acetate	2
Galbanum oil	1
	1000

EXAMPLE II

Petitgrain composition:	Parts by weight
Menthanyl acetate	250
Linalyl acetate	200
Linalool	200
Geraniol	150
α -Terpineol	65
β -Methyl 2-ethyl 5-isopropyl styrene	50
Geranyl acetate	50
1-limonene	35 10
	1000

EXAMPLE III

Verveine composition:	Parts by weight
Oil of lemon grass rect.	350
Citral 100%	280
Geraniol	100
Methyl ionone	75
Lemon oil messina, C.P.	70
Benzyl acetate	50
β ,2-dimethyl 5-tert.-butyl styrene	25
Hydroxycitronellal	25
Citronellal 10%	15
Neroline bromelia	10
	1000

From a consideration of the foregoing disclosure, it will

be evident that the initially recited object of the present invention has been achieved.

What we claim is:

1. A perfume composition comprising an effective amount of a compound of the formula

as an olfactory ingredient in a perfume carrier, in which R_1 is methyl or ethyl and R_2 is branched or nonbranched alkyl having 3-5 carbon atoms.

2. A perfume composition comprising as an olfactory ingredient an effective amount of β ,2-dimethyl 5-isopropyl styrene in a perfume carrier.
